METHOD AND MEANS OF APPLYING
PARTIAL COATINGS TO ARTICLESThomas E. Grieve, Corning, N. Y., assignor to
The Gorton Chocolate Company, Corning,
N. Y., a corporation of New York

Application August 5, 1931. Serial No. 555,305

22 Claims. (Cl. 91—3)

This invention relates to article coating, with reference more especially to candy manufacture and is intended to provide a commercially practical method or process and means of applying a mere partial or part-way coating to such articles in large-quantity production.

The manufacture of coated candies and confections has of course been common for a long time and there is nothing new per se in a partially coated product nor in a wholly coated product. Moreover, various machines have been developed to perform the work of coating these articles, some with considerable efficiency, but most of such machines are adapted to coat the articles either all over or else on top (or bottom) only and no really satisfactory way of accomplishing a mere partial coating thereof has heretofore been devised, other than the tedious method of hand-dipping which is too slow and expensive for practical commercial purposes. In providing a way to accomplish this partial coating at a rate and at a cost comparable to that of present machine practice in full or mere bottom coating, as will appear, the invention is believed to be a distinct advance and desirable contribution in the art.

It will be best understood by further description with reference to the attached drawing, illustrating the method along with one practicable embodiment of means for carrying it into effect, the latter being shown in the form of an attachment to an ordinary known type of coating machine.

In said drawing:

Fig. 1 is a side view representation of a conventional type of machine with attachments embodying and adapted to perform the method of the invention;

Fig. 2 is an enlarged sectional view of a portion of this machine better illustrating certain of the principal features involved; and

Fig. 3 is a plan view representation of the same portion of the machine, with parts broken away.

Briefly stated, the method consists in passing the articles through a puddle or wash of the coating substance at a depth covering them the desired extent, while supplying and counter-draining the puddle in a manner to maintain it at such depth and to cause a circulation or flowage trend thereof in direction and with force to counteract flotation or dislodgment influences upon the articles during the passage therethrough.

This and very simple means by which it may be accomplished are exemplified in the drawing.

The medium of passing the articles through

said treatment is advantageously provided by a moving reticular surface, such as an endless driven open-mesh wire belt 4, on which the articles are placed. This surface or belt may as in the illustrative example constitute the main conveyor element of an ordinary coating machine 5 to which the invention is shown applied, in which case its utilization for the purpose of the different method involved would require a shut-off of feed to the machine's normal discharge head (not shown).

As common to machines of the kind, a cooperating endless feed belt 6 at the forward end, upon which the articles are desirably pre-arranged in longitudinal rows provides for continuous successive depository thereonto. A similar belt 7 at the other end may receive the articles therefrom after coating for conveyance to a packing or gathering table (not shown). The last-mentioned belt is advantageously passed through or deliverable to a cooling chamber, represented by the hood 8, for the purpose of settling or hardening the coatings before final delivery to said table.

Passage as aforesaid through a "puddle or wash" deep enough for the desired coating is ordinarily liable to float or dislodge the articles from the conveying surface. According to this method however, such happening is prevented by supplying and draining the puddle in manner generating a flowage thereof overbalancing these forces. For such purpose, it is very appropriately formed by an overflow from a trough-like receptacle 9 supported close under the aforesaid wire belt, preferably between supporting rollers 10 therefor, so that the overflow will occur through the belt to the desired level thereabove. Packing 11 extending around the top edge of the receptacle serves to close any gap space and compel the overflow above rather than below the belt as also to minimize wear, while belt-supporting rollers at either side, as mentioned, will tend to laterally extend or spread the overflow. This is illustrated clearly by the enlarged view of Fig. 2, wherein the overflow or puddle is represented by x. The escape or drain of this overflow is of course caught and returned into the supply system of the apparatus or machine, in this instance by a pan and part of the casing shown under the receptacle.

The supply to said overflow is preferably by forced jet or stream discharge of the coating substance thereinto. This is shown effected through a single line series of nozzles 12 pending from a head 13 directly over the receptacle above

the conveying belt and therethrough expelling into the former. These nozzles, having flow-regulatory means represented at 14 and elevation adjustment means indicated at 15 are spaced 5 apart sufficiently for the articles moving in rows on said belt to pass therebetween or between the jets of substance discharging therethrough. Associated means such as illustrated by the wires 16 may advantageously be provided to guide the 10 articles all the way through the puddle or overflow area.

The aforesaid nozzles of course connect with a source of coating substance supply while the discharge therethrough is preferably by force-pump 15 action. In this instance the connection is made by piping 17 between their head (13) and the supply-circulating system or feed line 18 of the machine (5) to which the invention is applied. A continuous feed by action of said machine's 20 circulating pump 19 is accordingly assured. Its shut-off through normal discharge channels is conveniently effected by a valve 20 placed in the feed line beyond the tap connection thereonto.

It will be obvious that the depth of the puddle 25 formed by the overflow from the receptacle will depend upon the volume and force of discharge thereinto. Accordingly, the extent of the article coating may be controlled by regulation of the pump action and nozzle flow, a variation being 30 obtainable through either.

While the drainage is laterally over the edges of the receptacle above the belt level, the force of discharge from above will create a downward current trend with lateral component stronger 35 than the upward escape flow, thereby overbalancing or counteracting any flotation or dislodgment influences upon the articles passing through the puddle and so hold them down upon the conveying surface. This current trend or circulation 40 within the body of the puddle is indicated by the arrows in Fig. 2 of the drawing. The jets of substance discharging through the nozzles and striking the sides of the articles will assist in thus holding them down upon the conveying surface as also to assist in the coating thereof. The height of the articles to be coated 45 will suggest the distance at which said nozzles should be elevated above the belt. Generally, their ends should extend down below the tops 50 of the articles. If elevated too high thereabove, the articles are likely to and may be coated all over. On the other hand, only the bottoms thereof will receive a coating if the nozzles are lowered close to the conveying belt and the discharge therethrough is moderated to create a 55 very shallow puddle.

A commercially practical method of applying a mere partial or part-way coating to articles in large-quantity production is thus provided. Its 60 advantages will be readily apparent to those familiar with industrial candy manufacture.

Obviously moreover, the invention may be carried out in various ways and by various instrumentalities, so that it is not intended to be limited 65 by the appended claims to the specific features and apparatus shown.

Having thus described my invention, what I claim as new and desire to secure by Letters Patent of the United States is:

70 1. A process of coating the bottoms and sides of articles with a liquid substance, characterized by passing the articles on a moving surface through a puddle of the substance of a depth to only partially submerge the same and maintaining currents of supply and drainage of the sub-

stance in the puddle in direction and force to hold the articles down on said surface while passing through the puddle.

2. The process of coating the bottoms and sides of articles with a liquid substance, which consists 80 in passing the articles on a moving surface through a pool of the substance of a depth to only partially submerge the same and maintaining a supply and counter-drainage of the substance to the pool so as to set up currents of flowage therein in direction and force to counteract flotation or dislodgement of the articles during passage through the pool.

3. The process of coating the bottoms and sides 90 of articles with a liquid substance, which consists in passing the articles on a moving surface through a puddle of the substance of a depth to only partially submerge the same and supplying the substance to the puddle in a manner to maintain it at said depth and cause a circulation or flowage trend thereof in direction and force to counteract flotation or dislodgment influences upon the articles, during the entire passage through the puddle.

4. A process of coating the bottoms and sides 100 of articles with a liquid substance, characterized by passing the articles on a moving surface through a puddle of the substance at a depth less than the height or thickness of the articles, and holding the articles undislodged upon the 105 surface by currents of supply and counter discharge of the substance in the puddle during the passage therethrough.

5. A process of coating the bottoms and sides 110 of articles with a liquid substance, characterized by passing the articles on a moving surface through a puddle of the substance deep enough for partial submergence therein, while holding the articles undislodgably on the surface by predominately downward currents of the substance 115 flow in the puddle created by supply and counter-drainage of the same in proper direction and force.

6. In a method of partially coating articles 120 with a liquid substance, the expedient of passing the articles on a moving surface between discharging jets of the substance impinging thereagainst below their tops holding the articles firmly on the surface during such passage by force of the jet discharge and currents of downward 125 flow of the substance maintained in a counter-withdrawal thereof below the jets.

7. A process of coating articles with a liquid substance, characterized by conveying the articles 130 on a moving surface through a puddle of the substance while discharging jets of the same thereagainst and holding the article firmly on said surface during the passage through the puddle by force of the jet discharge and flowage of the substance therebelow in predominately downward 135 currents maintained by a simultaneous drainage of the puddle in counter-balance with such discharge.

8. In a method of coating candy articles and the like, the improvement which consists in passing the articles on a moving surface through a pool of the coating substance at a depth for the desired extent of coating the same, and maintaining currents of supply and drain-flowage of the substance in the pool in direction and with force 145 to counteract floatation or dislodgment influences on the articles during the entire passage therethrough.

9. In a method of coating candy, the improvement which consists in passing the candy on a 150

moving surface through a puddle of the coating substance at a depth for the desired extent of coating, while supplying and counter-draining the puddle so as to maintain currents therein in direction and force to counteract floatation or dislodgment influences on the candy during the entire passage therethrough.

10. A process of coating only the bottoms and sides of articles with a liquid substance, characterized by placing the articles on a movable surface, moving the surface with the articles thereon through a puddle area, and maintaining a puddle of the substance within said area at a depth to only partially submerge the articles and with currents of supply and drainage in direction and force to hold the articles undislodged upon said surface while moving through the puddle.

11. A process of coating articles with a liquid substance, which consists in placing the articles on a movable surface, passing the surface with the articles thereon through a puddle area, and maintaining a puddle of the substance within said area at a predetermined depth according to the extent of coating desired by a counter-balanced supply and drainage setting up currents of flow therein in direction and force to hold the articles against floatation or dislodgment on the surface while passing entirely through the puddle.

12. The method of coating articles with a liquid substance, which consists in conveying the articles on a surface over an open receptacle caused to overflow a supply of the substance in formation of a puddle thereabove at a level to which the coating is desired and supplying and draining the puddle in a manner to maintain currents of flow therein in direction and force to counteract floatation or dislodgment of the articles in the entire passage through the puddle.

13. The method of coating articles with a liquid substance, which consists in conveying the articles on a reticular surface between spaced downwardly discharging nozzles and over an open ended receptacle therebelow caused to overflow a supply of the substance to a level above said surface forming a paddle of a depth for the desired coating through which the articles are passed, supplying the substance through said nozzles and simultaneously draining the puddle so as to keep it at said level and maintain currents of flowage therein in direction and force to counteract floatation or dislodgment influences on the articles during the passage therethrough.

14. The method of coating the bottoms and part of the sides of articles with a liquid substance, which consists in conveying the articles on a moving surface through a puddle of the substance while supplying the puddle through spaced discharge nozzles thereover between which the articles are passed with an assisted or certain amount of coating therefrom and draining the puddle in substantial equalization with the supply rate so as to maintain currents of flowage therein in direction and force to counteract floatation or dislodgment influences on the articles during passage therethrough; the extent or height of the side coating of the articles being dependent essentially upon the depth of the puddle and the depth of the puddle being governable by the volume and rate of its supply and counterdrainage.

15. The method of applying a mere partial or part-way coating of a liquid substance to articles, which consists in passing the articles through a

puddle of the substance at a depth to cover them the desired extent, while supplying and counter-draining the puddle in a manner to keep it at such depth and maintain currents of flowage therein in direction and force to counteract floatation or dislodgment influences upon the articles during the passage therethrough.

16. In an article coating machine including a flat-surface conveyor for the articles to be coated, a receptacle having an open end supported under the conveyor and adapted to overflow thereabove in formation of a puddle of the coating substance, means for supplying the receptacle with the substance at a rate to cause its overflow and maintain a puddle at the desired level above said conveyor passing the articles therethrough, and means for maintaining currents of the substance supply and drainage in the puddle in direction and force to counteract floatation or dislodgment influences on the articles during the entire passage through the puddle.

17. In an article coating machine, means for conveying the articles along a straight path, means for forming a puddle of the coating substance over the surface of the conveyor through which the conveyed articles must pass with coating by submergence therein, means for supplying the substance so as to form and maintain a puddle of the desired depth upon said surface, and means for maintaining currents of the substance supply and drainage in the puddle in direction and force to counteract floatation or dislodgment influences on the articles during their entire passage therethrough.

18. In an article coating machine, a reticular conveyor for the articles, an open receptacle supported under the conveyor, a series of nozzles arranged over said receptacle and above the conveyor so as to discharge through the latter into the former, means for forcing a supply of the coating substance through said nozzles and means maintaining an overflow of the supply from the receptacle through and to a level above the conveyor in formation of a puddle with currents of said supply and overflow in direction and force to counteract floatation or dislodgment influences upon the articles while passing with the conveyor entirely through the puddle.

19. In an article-coating machine, a reticular conveyor for the articles, an open receptacle supported under the conveyor, a series of nozzles arranged over said receptacle and above the conveyor so as to discharge through the latter into the former, means for forcing a supply of the coating substance through said nozzles and means adapting the receptacle to overflow through and to a level above the conveyor so as to form a puddle in which currents of the supply and overflow are maintained in direction and force to counteract floatation or dislodgment influences on the articles during passage entirely therethrough, the depth of said puddle being governable by the volume and rate of supply force through said nozzles.

20. In combination with an article coating machine having a reticular conveyor for the articles and means for forcing a supply of the coating material to a discharge point; an attachment for coating only the bottoms and part of the sides of the articles, comprising an open receptacle supported under the conveyor, a series of nozzles arranged above the conveyor to discharge therethrough into said receptacle, means for diverting the force of coating substance supply into and through said nozzles, and means for

5 maintaining an overflow of the receptacle through and to a level above the conveyor in formation of a puddle with currents of the supply and overflow therein in direction and force to counteract flotation or dislodgment influences on the articles during passage therethrough with the conveyor.

10 21. In combination with an article coating machine having a reticular flat-surface conveyor for the articles and means for forcing a supply of the coating material to a discharge point; an attachment for coating only the bottoms and part of the sides of the articles, comprising an open receptacle supported under the conveyor, a series of spaced nozzles arranged above the conveyor to discharge therethrough into said receptacle, means for diverting the force of coating sub-

stance supply into and through said nozzles, means for guiding the articles between the nozzles, means for maintaining an overflow of the receptacle through and to a level above the conveyor in formation of a puddle with currents of the supply and overflow therein in direction and force to counteract floatation or dislodgment influences on the articles during passage with the conveyor through said puddle and means for returning the overflow to the supply source of the machine.

15 22. An article-coating machine attachment according to claim 19, wherein the nozzles are adjustable in end elevation above the conveyor and include means for regulating the flow therethrough.
